COLLAPSIBLE BOAT

Filed Oct. 25, 1933

FIG. I.

FIG. 2

上

INVENTOR;
PHILIP J. HUEFNER
BY Arthur O. Eckert
ATTORNEY

of claims in this application relating to a collapsible boat having an air chamber, an air chamber being defined by a front section and a rear section, the front section being of substantially the same height, size and shape and are bent centrally at their tops, so that the top edge of both walls is lower than the sides 7 of the front section 4 and the sides 10 of the rear

section 5. In the front wall 12 are formed two perforations, one near each of the side walls, and in the rear wall 8 are formed perforations similarly positioned. Numerals 13 designate bolts passing through these holes, which bolts secure the front wall 12 and the rear wall 8 together near their top edges. In order to make a water proof joint at the jointure, between the bottoms 6 and 9, the bottom 6 is extended slightly longitudinally so as to come into frictional engagement with the forward portion of the bottom 9. Numerals 14 designate the conventional ribs and numerals 15 the conventional oarlocks.

In the extreme forward portion of the front section 4 is connected the plate 16, which is secured to the sides 7 in a plane parallel to the bottom by any conventional means, such as soldering. Numeral 17 designates an air container of the same shape and size as the space between the plate 16, the sides 7 and the bottom 6. The air container 17 is slid from the rear under the plate 16 and remains there, while the boat is in use in frictional engagement with the plate 16, the bottom 6 and the sides 7. Numeral 18 designates an air container, which is positioned in the rear portion of the rear section 5, and is in sliding engagement on the bottom 9 and in sliding engagement with the sides 10, and when in position comes in contact with the rear wall 11. Numeral 19 designates a plate that is in sliding engagement with the sides 10 immediately above the air container 18. The plate 19 performs the function of a seat for a passenger as does the plate 16, previously described. A third air container 20 is positioned in the rear portion of the front section 4 in physical engagement with the rear wall 8 of the front section 4.

The top of the rear wall 8 of the front section 4 is bent over in a state of parallelism with the bottom 6, so that it comes in contact with the upper side of the air container 20. Numeral 21 designates a seat, which is supported on two U shaped elements 22. The parallel portions of the U shaped elements 22 are spaced apart, a distance equal to the width of the air container 20 and the rear wall 8 and the front wall 12, so that when the U shaped elements 22, which are secured to the seat 21 are placed in position they are in frictional engagement with the forward side of the air container 20 and the forward side of the inner portion of the front wall 12. In order to positively secure the U shaped elements 22 to the air container 20 and the front wall 12, screws 23 are employed, one of each of which passes through the

UNITED STATES PATENT OFFICE

COLLAPSIBLE BOAT

Philip J. Huefner, Belleville, Ill.

Application October 25, 1933, Serial No. 695,101

1 Claim.

The object of my invention is to devise a collapsible boat. More specifically my invention relates to small boats or skiffs that are made in sections that are selectively secured together. The purpose of making, particularly a small boat "knocked down" is that it may be conveniently carried or transported on an ordinary vehicle, such as an automobile.

The boat of the type, herein described, may be taken apart or disassembled, so that the entire boat may be secured to a rack on the rear of an automobile. The boat is preferably made of metal, although it can also be made of wood. It is made in sections or compartments, each one of which is water proof, and of such weight and construction that it will float on the surface of water. The purpose of this is to prevent the sinking of the entire boat, in the event that water leaks into one section.

Among the further objects are to supply detachable air containers to be positioned in the boat to add to its buoyancy.

Still a further and one of the principal objects is to secure a seat over the jointure between both sections, in such a manner that the seat supporting means also functions as section securing means. The boat is so constructed that it may be made of few and simple parts that lend themselves readily to multiple production. The boat may be cheaply made.

With these and other objects in view, my invention has relation to certain novel features of construction and arrangement of parts as will be hereinafter more fully described, pointed out in the claim and illustrated in the drawing, in which

Fig. 1 is a plan view of my device.

Fig. 2 is a longitudinal sectional elevation taken on the line 2-2 of Fig. 1 and Fig. 3 is an enlarged fragmental sectional elevation taken on the line 3-3 of Fig. 1.

Numeral 4 designates the front section and numeral 5 the rear section. Numeral 6 designates the bottom of the front section 4, numerals 7 the sides of the front section 4 and numeral 8 the rear wall of the front section 4. Numeral 9 designates the bottom of the rear section 5, numerals 10 the sides of the rear section 5, numeral 11 the rear wall of the rear section 5 and numeral 12 the front wall of the rear section 5.

The front wall 12 of the rear section 5 and the rear wall 8 of the front section 4 are of substantially the same height, size and shape and are bent centrally at their tops, so that the top edge of both walls is lower than the sides 7 of the front section 4 and the sides 10 of the rear

lower portion of one of the parallel portions of the U shaped elements 22.

Numeral 24 designates a plate of wood or other similar material, which is placed between the inner surface of the front wall 12 and the parallel portions of the U shaped elements 22. The screws 23 come into frictional engagement with the plate 24 and force it against the front wall 12. By this means the seat 21 is secured to the boat and the front section 4 and the rear section 5 of the boat are additionally secured together.

15 Numeral 25 designates the conventional grating positioned on the floor of the front section 4 and numeral 26 designates a like grating positioned on the floor of the rear section 5. Obviously, the boat may be made of a plurality of sections rather than two, as shown in the drawing and as hereinbefore described. In each instance, they will, however, be separate compartments and will be secured together as indicated. By the jointures 20 between the sections indicated, the sides and bottom are brought in close frictional engagement with each other and prevent water from leaking into the sections through the jointures.

A boat comprising sections, each of which is water tight, detachable air containers positioned in each section of said boat, each section of said boat being selectively detachable from its adjoining section, section jointure means, seats secured in said boat over the jointure between adjacent sections, one of said detachable air containers being positioned under each, but independent of said seats, the section jointure means being U shaped elements secured to the seats and held in frictional engagement with the adjoining section walls, and said air containers positioned under said seats, screws in threaded engagement in the lower portion of one of the parallel portions of said U shaped jointure elements, plates positioned between the inner surface of one section wall and the parallel portions of said U shaped jointure elements, so that said screws come into frictional engagement with said plates, so that when said screws are tightened the adjacent walls of the adjoining sections, the air containers under said seats and the jointure means will be securely tightened together, thereby providing dual means for holding the adjoining sections together.

PHILIP J. HUEFNER.
